Des. 228,066
Patented Aug. 7, 1973

228,066

MODULAR BATHROOM

Edmund F. Humphries, Jr., Tulls Creek Road,
Moyock, N.C. 27958

Filed May 14, 1971, Ser. No. 143,717

Term of patent 14 years

Int. Cl. D23—02

U.S. Cl. D23—49

FIG. 1

FIG. 2

FIG. 3

FIG. 5

FIG. 4

FIG. 7

FIG. 8

FIG. 6

FIG. 9

FIG. 1 is a perspective view taken from the top, one side and one end of a modular bathroom showing my new design;

FIG. 2 is another perspective view taken from the same side and end with the center portion broken away for convenience of illustration;

FIG. 3 is an elevational view taken from the side opposite that shown in FIG. 1;

FIG. 4 is an elevational view taken from the end opposite that shown in FIG. 1;

FIG. 5 is an elevational view taken from the end shown in FIG. 1;

FIG. 6 is a cross sectional view taken on line 6-6 of FIG. 3;

FIG. 7 is a cross sectional view taken on line 7-7 of FIG. 3;

FIG. 8 is a cross sectional view taken on line 8-8 of FIG. 5; and

FIG. 9 is a cross sectional view taken on line 9-9 of FIG. 5.

The broken line representation of fixtures in FIGS. 2, 5, 6, 8 and 9 are for purposes of illustration only.

I claim:

The ornamental design for a modular bathroom, substantially as shown and described.
